UNITED STATES PATENT OFFICE.

THOMAS E. MURRAY, OF NEW YORK, N. Y.

FUSE-SWITCH.

1,112,156.

Specification of Letters Patent. Patented Sept. 29, 1914.

Application filed November 28, 1913. Serial No. 803,870.

To all whom it may concern:

Be it known that I, THOMAS E. MURRAY, a citizen of the United States, residing at New York; in the county of New York and State of New York, have invented a certain new and useful Improvement in Fuse-Switches, of which the following is a specification.

The invention is a fuse switch of simple construction, in which a removable cylindrical cartridge fuse case co-operates with contacts disposed in a tubular casing. The fuse case or plug is provided with an insulating handle, by which it may be introduced into or removed from the casing.

In the accompanying drawings—Figure 1 is a longitudinal section of my fuse switch. Fig. 2 is a cross section on the line A, A of Fig. 1. Fig. 3 is a bottom view of the insulating block.

Similar numbers of reference indicate like parts.

The tubular metal casing comprises a body portion 1, screwed at its ends into sleeves 2, 3, and side projections 4, 5 screwed into offsets on the walls of said sleeves. Within the body portion 1 is a tubular lining 6 of insulating material, closed at its upper end. Within said closed end is disposed an inverted cup-shaped contact 7, having a longitudinally grooved arm 8 which enters projection 4 through an opening in lining 6. Above the arm 8 is a plate 9 of insulating material, shaped, as shown in Fig. 3, to fit upon arm 8 and to rest upon the closed end of lining 6. Above the plate 9 may be a spacing block 10 of insulating material, upon which bears a screw plug 11 entering the upper extremity of sleeve 2. Also in projection 4 is an insulating block 12 grooved to receive a grooved metal plate 13 which faces arm 8, as shown in Fig. 2. One circuit terminal 14 enters between arm 8 and plate 13. The insulating block 9 is held in place by a screw 15, and the block 12 is held in place by screws 15*.

In the projection 5 is an insulating block 16 similar to block 12 and held in place by screws 17. Said block carries a grooved contact plate 18 similar to plate 13. At the lower part of lining 6 is an annular contact 19, having an arm 20 which enters projection 5 through an opening in said lining and is shaped similarly to arm 8. Above extension 20 is an insulating block 21, secured in place by screw 22. The other circuit terminal 23 is received between arm 20 and plate 18.

24 is a cartridge fuse case, having the usual metal end caps 25, 26. Said fuse case is secured to a handle 27 of insulating material by a screw 28 countersunk in said handle. On the exterior of sleeve 3 are spring hooks 29 which engage with a flange 30 on said handle.

When it is desired to bring the fuse into circuit, the fuse case 24, by means of handle 27, is inserted as a plug into body portion 1 until end cap 25 is seated in contact 7, when end cap 26 registers with contact 19, thus completing circuit from one terminal, as 14, through the fuse to the opposite terminal 23.

In the embodiment of my device here shown, the hooks 29 first enter vertical recesses 31 in the edge of flange 30 and then enter circumferential recesses having upper inclined undercut edges 32. By rotating the handle, the edges 32 running over the hooks ends jam the upper end cap of fuse case 24 tightly into contact 7 thus locking the plug in place.

It is to be particularly noted that when the fuse is blown, or for any reason requires attention, the fuse case or plug is wholly removed from its inclosing casing, and away from all live connections. To substitute a new fuse case, all that is required is to release the screw 28 holding the old one to the handle, and connect the new one to said handle by the same screw.

I claim:

1. A tubular casing, a cup-shaped contact and an annular contact disposed within said casing, a cylindrical fuse plug received in and having external contacts co-operating with said casing contacts, hooks on said casing, and a flange on said plug having in its edge circumferential recesses co-operating with said hooks upon the rotation of said plug to force the end of said plug into said cup-shaped contact.

2. A casing having a tubular body portion and tubular projections extending laterally therefrom, fixed contacts in said body portion, arms on said contacts extending into said projections, means in said projections for connecting said arms to circuit terminals, and a removable cylindrical fuse plug received in said body portion and having external contacts co-operating with said fixed contacts.

3. A tubular casing, contacts therein, a

removable cylindrical fuse plug received in
said casing and having external contacts co-
operating with said casing contacts, a flange
on said plug abutting against the circumfer-
ential edge of said casing, and hooks on said
casing engaging said flange and holding
said casing and plug contacts in coöperative
relation.

In testimony whereof I have affixed my
signature in presence of two witnesses.

THOMAS E. MURRAY.
